UNITED STATES PATENT OFFICE.

JOHN ROGERS, OF BRIDGEPORT, CONNECTICUT, ASSIGNOR OF ONE-FOURTH TO THOMAS E. LAKE, OF STRATFORD, CONNECTICUT; ONE-FOURTH TO HENRY F. BLAKELEY, OF BRIDGEPORT, CONNECTICUT; AND ONE-FOURTH TO ISIDOR ROSENZWEIG, OF MILFORD, CONNECTICUT.

SELF-CLOSING BASIN FAUCET.

Application filed December 31, 1923. Serial No. 683,624.

To all whom it may concern:

Be it known that I, JOHN ROGERS, citizen of the United States, residing at Bridgeport, in the county of Fairfield and State of Connecticut, have invented certain new and useful Improvements in Self-Closing Basin Faucets; and I do hereby declare the following to be a full, clear, and exact description of the invention, such as will enable others skilled in the art to which it appertains to make and use the same.

My invention relates to self closing basin faucets, and it consists in certain details of construction comprising a body having a valve and its seat in one chamber, and a plunger with an underlying packing located in a separate chamber and having a plunger stem in contact with the valve, means located adjacent to the plunger to be operated outside of the faucet for opening the valve and compressing the packing to prevent leakage by the plunger stem.

Referring to the accompanying drawings, wherein the same figures of reference indicate like parts throughout the several views:

Figure 1 represents a central sectional and partially broken view of the faucet body, showing the valve closed, and broken view of the water supply pipe;

Figure 2 is a central sectional view of the body of the faucet showing the valve unseated, broken view of the supply pipe and discharge nozzle;

Figure 3 is an end elevation of the body of the faucet, looking in the direction of arrow *a* of Figure 1;

Figure 4 is a sectional view of the lower end of the faucet body on line 4—4 of Figure 1;

Figure 5 is a reduced broken sectional view of the upper part of the faucet body showing modified means for unseating the valve and compressing the packing ring;

Figure 6 is a view of the position of the elements shown in Figure 5 when the valve is unseated;

Figures 7, 8, 9 and 10 are detail views of the valve construction;

Figure 11 is a view of a partially assembled valve;

Figure 12 is an enlarged view of the assembled valve; and

Figure 13 is a modified view of the assembled valve.

The body 1 has the chambered end 2 in which is located the plunger 3 and the packing washer 4. The cap 5 is removably secured to the body 1 and is provided with the semi-circular shaped recess 6. Within this recess is located the semi-circular member 7 shaped to conform to the curved wall of the recess 6 and contact therewith.

8 is the valve chamber, 9 the valve seat, and 10 the discharge chamber. The valve may be composed of several parts to provide means for destroying the noise incidental to the impinging of two metal surfaces when the valve is seating. The valve disk 11 has the taper face 12 adapted to register with the valve seat 9. The guide head 13 and body 14 being integral with the valve disk 11. The collar 15 has the recess 16 to admit the disk 17, which disk may be of rubber or other like non-metallic material adapted to serve as a muffler or buffer to deaden the sound on the seating of the valve. Central holes 18, 19, 20, are respectively provided in these three members to receive the pin 21 to lock all of the members together, as shown in Figure 12.

In the valve construction shown in Figure 13, the body 14, head 13 and the valve disk 11 are integral. The non-metallic buffer 17 and collar 15, are held in proper relation with the disk 11 by simply heading over the projecting body 14 as shown. This construction dispenses with the pin 21 and hole 18, shown in the other valve construction views.

The spaced longitudinal ribs 22, Figures 1, 2, and 3, project inwardly from the bore or valve chamber 8 to provide for the collar 15 of the assembled valve. The spaced longitudinal ribs 23, see also Figure 4, provide bearings in the bore 32, on the opposite side of the valve seat 9, for the head 13 of the assembled valve. While these spaced ribs form bearings for the valve, they also permit an uninterrupted flow of water when the valve is unseated.

Normally the handle 25 is in the vertical position shown in Figure 1. Depressing this handle in any direction, Figure 2, will tilt its semi-circular base 7 and cause said

base to force inward the plunger 3 and unseat the valve and permit water to flow therethrough to the discharge nozzle 26.

When the plunger 3 is thus forced inward it will compress the packing ring to an extent that will effectually prevent water escaping by the plunger stem 24 while the valve is unseated. The water discharge will continue so long as the handle 25 is depressed, but as soon as it is released, the force of the incoming water will close the valve and also force the plunger 3 against the inner inclined face of the base 7, and reestablish its normal position, as shown in Figure 1.

This arrangement for manually opening the valve, and automatically closing it, prevents an undue waste of water as none can pass by the valve only while the handle is manually depressed, for the instant the handle is released, the flow of water ceases.

The modification shown in Figures 5 and 6 relates, as previously mentioned, to mechanism for unseating the valve and compressing the packing washer. The cam face member 27 serves the same purpose as the member 7 in Figures 1 and 2, and the cam face member 28 serves the same purpose as the member 3. The handle 29 is mounted on the outer end of the stem 30, and the cam face member 27 is horizontally rotated in either direction thereby. The angular stem 31 of the cam face member 28 will prevent the rotation of said member but it will be depressed by the rotation of the member 27 against the packing washer 4 as shown in Figure 6. The lower end of the stem 31

will serve the same purpose for unseating the valve as the stem 24 in Figures 1 and 2. As soon as the handle 29 is released, the incoming force of water will reseat the valve and reestablish the normal position of the several members as shown in Figure 5.

Having thus described my invention what I claim is:—

1. In a faucet of the character described, comprising a body having a valve chamber and valve seat, a sectional valve construction comprising a valve disk for the valve seat, a guide head and a body connecting the valve disc and head, a collar and a buffer located between the valve disk and collar, means for uniting the valve sections, and means for unseating the valve against the water pressure.

2. In a faucet of the character described, comprising a body having a bore and a valve seat therein, a valve comprising a guide head, a valve disk for the valve seat, a collar and a non-metallic buffer held between the valve disk and collar, spaced longitudinal ribs integral with the walls of the bore on each side of the valve seat to form bearings for the valve, and means for unseating the valve.

3. A sectional valve construction for faucets, comprising a valve disc, a guide head and an intermediate body portion integral with the disc and head, a collar, a non-metallic buffer member located between the valve disc and collar, and means for uniting the sections together.

In testimony whereof I affix my signature.
JOHN ROGERS.
